UNITED STATES PATENT OFFICE.

WILLIAM D. CROCKER, OF BUHL, ALABAMA.

LIVE-ROLLER LUMBER-CONVEYER.

1,191,403.

Specification of Letters Patent. Patented July 18, 1916.

Application filed March 28, 1914. Serial No. 827,844.

To all whom it may concern:

Be it known that I, WILLIAM D. CROCKER, a citizen of the United States, residing at Buhl, in the county of Tuscaloosa, State of Alabama, have invented certain new and useful Improvements in Live-Roller Lumber-Conveyers; and I do hereby declare the following to be a full, clear, and exact description of the invention, such as will enable others skilled in the art to which it app pertains to make and use the same.

This invention relates to conveyers and has special reference to a conveyer adapted to convey lumber around curves and up and down inclines.

The principal object of the invention is to provide an improved general construction of conveyers of this type.

A second object of the invention is to provide a flexible conveyer which is adjusted to various curves and which will still operate to convey the lumber to the point de sired.

A further object of the invention is to provide an improved conveyer wheel for use in connection with such a conveyer.

With the above and other objects in view the invention consists in general of certain novel details of construction and combination of parts hereinafter fully described, illustrated in the accompanying drawings and specifically claimed.

In the accompanying drawings, like characters of reference indicate like parts in the several views, and:—Figure 1 is a side elevation of a conveyer constructed in accordance with this invention. Fig. 2 is a plan view of such a conveyer showing the curve thereof. Fig. 3 is an enlarged detail view showing one of the rollers used in connection herewith. Fig. 4 is a section on the line 4—4 of Fig. 3. Fig. 5 is a detail section on the line 5—5 of Fig. 1. Fig. 6 is a detail section on the line 6—6 of Fig. 2. Fig. 7 is a plan view of one of the bearings. Fig. 8 is an end view of the same. Fig. 9 is a detail view showing a form of roller especially adapted for handling planks.

In carrying out the objects of this invention there are provided a series of supports 10 which may be made of timber or the like material and these supports are connected at their upper ends by means of struts or beams 11 which serve to support a series of 55 oppositely disposed bearing blocks 12 where through extend a shaft 13. The supports 10

may be varied in height and may be arranged in any curve desired but when arranged in a curve the bearing blocks 12 are arranged radially of said curve. Located centrally 60 of each of the shafts 13 is a sprocket wheel 14. Beneath the supports 11 are other bearing blocks or bearings 15 wherein are journaled shafts 16 carrying the idler wheels 17. Running over the sprockets 14 and idler 85 wheels 17 is a chain 18 which is driven from a sprocket 19 located at one end of the conveyer. On the shaft 13 of the sprocket 19 is a belt pulley 20 which is connected by means of a belt 21 with a belt pulley 22 lo cated on a shaft 23. This shaft 23 is also provided with a belt pulley 24 which is connected by a belt 25 with the belt pulley of any desired engine not deemed necessary here to be shown. On each side of each 75 sprocket 14 is a hub 26. This hub in each instance is locked to the shaft by a key 27 and a set screw 28. On each shaft 13 inside of the respective bearing block is a collar 29 which is secured on the shaft by means of 30 a key 30 and a set screw 31. Between the collars 29 and hub 26 is secured a frusto conical roller 32 having a hollow portion 33 wherein the hub 26 of the specific shaft fits. The two rollers on each shaft are so 85 arranged that the minor bases of the frust cones are faced toward each other so that a species of trough shape device is formed and on each of these rollers there is provided a series of prongs 37.

It is to be noted that the chain 18 is flexible, laterally as well as horizontally and therefore that the chain can bend around curves as are illustrated in Fig. 2 or any other curves which may be desired. 95

From the foregoing it will be seen that a device of this kind can be erected to cover any ground, no matter how irregular its surface may be, and that the lumber will be conveyed up or down the conveyer at any 100 vertical or horizontal angle or curve that may be required since the flexibility of chain will cause the various flights or pronged rollers to revolve simultaneously and thereby advance the lumber along the 105 conveyer.

There has thus been provided a simple and efficient device of the kind described and of the character specified.

It will be obvious that many minor 110 changes may be made in the form and construction of this invention without depart

ing from the material principles thereof. It is not therefore desired to confine the invention to the exact form herein set forth, but it is wished to include all such as properly come within the scope claimed.

Having thus described the invention, what is claimed as new, is:—

In a conveyer of the class described, a support, a series of shafts arranged in spaced relation along said support, a pair of independent conveyer rollers on each shaft, said rollers being substantially conical with their inner ends opposed and provided

with recesses, sprocket wheels on the shafts between the rollers and having the ends of their hubs engaged in the recesses and with the adjacent ends of the rollers to limit the movement of the rollers toward each other, and a universally flexible chain engaged with the sprockets.

In testimony whereof, I affix my signature, in the presence of two witnesses.

WILLIAM D. CROCKER.
